[57] **CLAIM**

The ornamental design for a mop, as shown and described.

DESCRIPTION

FIG. 1 is a front elevational view of a mop, showing my new design, with the rear elevation being identical;
FIG. 2 is a right side elevational view, the left side being identical thereto;

FIG. 3 is an enlarged partial front elevational view thereof;

FIG. 4 is an enlarged bottom view thereof;

FIG. 5 is an enlarged partial right side elevational view thereof;

FIG. 6 is an enlarged partial front elevational view of a second embodiment of a mop, with the rear elevation being identical;

FIG. 7 is an enlarged partial view of the right side of FIG. 6 with the left side being identical thereto;

FIG. 8 is an enlarged partial front elevational view of a third embodiment of a mop, with the rear elevation being identical;

FIG. 9 is an enlarged partial view of the right side of FIG. 8 with the left side being identical thereto.
